(57) **CLAIM**

The ornamental design for a food preparation container, as shown and described.

DESCRIPTION

FIG. 1 is a top perspective view of the food preparation container, showing the new design;

FIG. 2 is a bottom perspective view of the food preparation container thereof;

FIG. 3 is a front elevational view of the food preparation container thereof;

FIG. 4 is a left side elevation view of the food preparation container thereof;

FIG. 5 is a top plan view of the food preparation container thereof;

FIG. 6 is a bottom plan view of the food preparation container thereof;

FIG. 7 is a top exploded perspective view of the food preparation container thereof; and,

FIG. 8 is a bottom exploded perspective view of the food preparation container thereof.

A rear elevation view of the food preparation container is a mirror image of the front elevational view of the food preparation container illustrated in FIG. 3.

A right side elevation view of the food preparation container is a mirror image of the left side elevational view of the food preparation container illustrated in FIG. 4.
